UNITED STATES PATENT OFFICE.

WALTER E. HUENEFIELD, OF CINCINNATI, OHIO, ASSIGNOR TO THE HUENEFIELD COMPANY, OF CINCINNATI, OHIO.

HYDROCARBON-BURNER.

1,070,604.

Specification of Letters Patent. Patented Aug. 19, 1913.

Application filed September 6, 1912. Serial No. 718,936.

To all whom it may concern:

Be it known that I, WALTER E. HUENEFIELD, a citizen of the United States, residing at Cincinnati, in the county of Hamilton and 5 State of Ohio, have invented certain new and useful Improvements in Hydrocarbon-Burners; and I do hereby declare the following to be a full, clear, and exact description of the invention, such as will enable 10 others skilled in the art to which it appertains to make and use the same.

This invention relates to improvements in hydrocarbon burners and more particularly to such as are adaptable for use with "oil 15 stoves",—the object of my present invention being to provide simple and efficient means for raising and lowering the parts forming the combustion chamber member and for locking said parts in their normal 20 lower position and sustaining the same in elevated position over the wick carrying member of the device.

With this object in view, the invention consists in certain novel features of construction and combinations of parts as hereinafter set forth and pointed out in the 25 claims.

In the accompanying drawings, Figure 1 is a sectional view of the device with the 30 parts in their normal operative position. Fig. 2 is a similar view showing the parts forming the combustion chamber, in elevated position. Fig. 3 is a transverse sectional view, on the line $x-x$ of Fig. 1, and 35 Fig. 4 is a transverse sectional view, on the line $y-y$ of Fig. 2.

The wick-tube member of the device comprises two concentric tubes 1—2, separated sufficiently to form a wick chamber between 40 them, the lower end of said chamber being closed in any suitable manner. The nipple 3 is secured to the outer wick tube 1 for attachment to a supply pipe and this nipple communicates with the lower portion of the 45 wick chamber. The upper end of the outer wick-tube is provided with an outwardly projecting annular flange 4 which is depressed somewhat, forming an annular rib 5 at the upper extremity of the tube 1. The 50 inner wick tube 2 is provided with a depressed inwardly projecting flange 6 (the inner edge of which may be bent downwardly as at 7), and an annular rib 8 is thus formed at the upper extremity of said 55 inner tube 2. A wick 9 is located within the

wick chamber between the tubes 1 and 2 and provided with a perforated metal wick holder 10. A hollow boss 11 is located on the outer tube 1 and communicates with the wick chamber and from this boss, a tube 12 60 projects in a diagonal direction,—said tube 12 and boss 11 constituting suitable bearings and housings for a shaft 13 which carries a toothed wheel 14 located within the boss 11 and adapted to mesh with perforations of 65 the wick holder for raising the wick when the shaft 13 is turned in one direction and for lowering said wick when the shaft is turned in the other direction. A suitable knob or wheel 15 is secured to the 70 free end of the shaft 13 to facilitate the manual operation of the wick raising and lowering devices. By so forming the upper ends of the wick tubes 1—2 as to provide annular ribs adjacent to the wick and separating the upper end of the latter from the flanges 4—6, any charred portions of the latter can be readily removed without becoming lodged in the immediate vicinity of 75 the wick and thus the burner can be easily 80 kept clean.

The annular flanges at the upper ends of the wick tubes 1 and 2 constitute seats for the lower ends of spaced foraminated shells 16 and 17 which form a combustion chamber 85 18 between them, said shells constituting the major portion of the combustion chamber member of the device.

The shells 16—17 are surrounded by a casing 19 which is spaced from the outer shell 17 and is open at its upper end,—the lower end of said casing being provided with an inwardly projecting bottom flange 20 having a plurality of perforations 21. The upper end of the shell 16 may be provided with a fixed cap or head 22 having suitable perforations and the lower end of 90 said inner shell may be provided with a perforated cap 23. The shells 16 and 17 and the casing 19 may be held in proper 95 relation to each other by means of transverse rods 24 which pass through them.

A spider 25 comprising a plurality of radial arms, is fixed within the inner wick tube 2 and constitutes a part of the raising, lowering and locking means for the combustion chamber member of the device. A cylindrical portion 26 depends from the inner shell 16 or from the lower cap 23 thereof 100 and enters the cylindrical space formed by 110

the inner wick tube and serves to guide the combustion chamber member in its vertical movements. The lower end of the cylinder 26 is notched or recessed so as to form a plurality of depending legs 27, each having a beveled edge 28, and each leg 27 is notched at its lower end to form a seat 29 and a stop 30. One of the legs 27 is provided above its lower end with a horizontal elongated slot 31 so that this leg will be made approximately L-shaped or hooked shaped.

When the shells forming the combustion chamber member are in their normal operative positions, they will be supported upon the annular flanges at the upper ends of the wick tubes 1 and 2 and the legs 27 will be disposed between the arms of the spider 25 but without actual contact with the latter.

When the shells 16 and 17 shall have been thus disposed, the combustion chamber member with its cylindrical extension 26 can be turned so that one of the arms of the spider will enter the elongated slot 31 in one of the legs 27 and the parts will then be locked against vertical movement. By making the slot 31 of appreciable length, the shells 16-17 can be partially rotated back and forth until they shall have become accurately seated upon the annular flanges of the wick tubes 1 and 2 and thus prevent any detrimental air currents entering in close proximity to the upper end of the wick. The casing 19 is provided with a suitable knob or handle 32 for manipulating the combustion chamber member, to raise the same above the wick or to lower said combustion chamber member as will now be explained. Assuming that the shells 16 and 17 are resting upon their seats on the wick tubes 1 and 2 and it is desired to raise said shells; the operator will turn said shells and casing and the beveled edges 28 of the legs 27, riding on the arms of the spider 25, will cause said shells and casing (which compose the combustion chamber member) to rise and when the seats 29 shall have become disposed upon the upper edges of said arms of the spider, the combustion chamber member will be supported in its raised position above the wick. The stops 30 at the lower ends of the legs 27 will engage the arms of the spider and prevent the combustion chamber member from being turned too far. After the wick shall have been lighted, the operator will turn the combustion chamber member in the reverse direction far enough to move the seats 29 off of the arms of the spider and then the weight of the parts will be sufficient to cause said combustion chamber member to move downwardly and become seated at the upper ends of the wick tubes. By further rotation of the combustion chamber member the cylindrical guide portion 26 will be partly rotated and its L-shaped leg will be caused

to coöperate with one of the arms of the spider to lock the combustion chamber member against vertical movement.

Having fully described my invention what I claim as new and desire to secure by Letters-Patent, is:

1. In a hydrocarbon burner, the combination with a wick tube member and a combustion chamber member, of an extension depending from the combustion chamber member and movable within the wick tube member, said extension forming a guide for the combustion chamber member, said extension having a plurality of inclined edges, and arms fixed within the wick tube members to be engaged by the inclined edges of said extension to effect the raising of the combustion chamber member when the latter is turned.

2. In a hydrocarbon burner, the combination with a wick carrying member and a combustion chamber member, of a spider secured to one of said members, an extension on the other member, said extension provided with a plurality of inclined edges to coöperate with said spider to raise the combustion chamber member, said extension also having seats adjacent to the free ends of its inclined edges to rest upon said spider and sustain the combustion chamber member in elevated position.

3. In a hydrocarbon burner, the combination with a wick carrying member and a combustion chamber member, of a spider secured on one of said members, an extension on the other member, said extension provided with a plurality of inclined edges to coöperate with said spider to raise the combustion chamber member, said extension also having seats adjacent to the free ends of its inclined edges to rest upon said spider and sustain the combustion chamber member in elevated position, and stops adjacent to said seats to limit the rotary movement of the combustion chamber member in one direction.

4. In a hydrocarbon burner, the combination with a wick tube member and a combustion chamber member, of a spider fixed within the wick tube member, and an extension depending from the combustion chamber member and entering the wick tube member, said extension having inclined edges and seats to coöperate with said spider for raising the combustion chamber member and supporting the same in raised position.

5. In a hydrocarbon burner, the combination with a wick tube member, a spider therein, and a combustion chamber member, of a guiding extension depending from the combustion chamber member and entering the wick tube member, said extension having inclined edges, seats and an open slot to coöperate with the spider in the wick tube member for raising the combustion chamber

member, for sustaining the latter in raised position and for locking said combustion chamber member in its lowered operative position.

- 5 6. In a hydrocarbon burner, the combination with a wick tube member and a combustion chamber member, of a part secured within and concealed by one of said members and having an inclined edge and a seat,
10 and an engaging device secured to the other member and entering the first-mentioned member to coöperate with said inclined edge and seat therein to raise the combustion chamber member when the latter is turned
15 and support the same in elevated position.

7. In a hydrocarbon burner, the combination with a wick tube member and a combus-

tion chamber member, of a spider secured to one of said members, an extension on the other member, said extension having inclined edges, seats, and an open slot to coöperate with the spider in the other member for raising the combustion chamber member, for sustaining the latter in raised position and for locking said combustion chamber in its lowered operative position.

In testimony whereof, I have signed this specification in the presence of two subscribing witnesses.

WALTER E. HUENEFELD.
